UNITED STATES PATENT OFFICE.

ROBERT L. DAVIS, OF LINCOLN, NEBRASKA,

INFANT'S TOILET-BED.

1,366,064.

Specification of Letters Patent. Patented Jan. 18, 1921.

Application filed March 29, 1920. Serial No. 369,577.

To all whom it may concern:

Be it known that I, ROBERT L. DAVIS, a citizen of the United States, and resident of Lincoln, in the county of Lancaster and State of Nebraska, have invented certain new and useful Improvements in Infants' Toilet-Beds, of which the following is a specification, reference being had therein to the accompanying drawing.

- 10 Very young children not yet able to occupy sitting position, usually need a great deal of attention whether sick or well in order that their bodies and clothing may be kept clean, and the object of this invention
15 is to materially lessen the difficulty suggested. This is done by providing a peculiar infant's bed, for temporary use from time to time as occasion may require, so constructed as to avoid very largely, at least, contaminating the person or clothing of the infant by bodily wastes and at the same time to avoid danger of chilling any part of the child's body.

In the accompanying drawings,

- 25 Figure 1 is a perspective view of the apparatus employed.

Fig. 2 is a vertical cross section of the same devices.

- 30 In these figures, A represents a sort of elongated box without bottom and having above a partial top consisting of two equal plates B, B fixed to the walls of the box, extending from end to end thereof, and each sloping from the corresponding lateral wall of the box toward the medial vertical plane of the box but not extending fully to that plane, whereby the lower edges of the plates are separated by an open passage C. Above the box, near one end thereof, is a 35 fixed rod D supported by brackets E rising from the lateral walls of the box, and upon the plates between the rod and the opposite end of the box is usually placed a small soft mat or pillow F shown in dotted lines.
40 In use, the box is placed over a common waste receptacle G, shown in dotted lines, and so adjusted that the receptacle may be directly below the proper part of the passage C. At the proper time, readily deter-

mined by the mother after a few days' experience in caring for the particular child, the infant is placed with its back upon the pillow and with its legs slightly flexed and supported by the rod. Waste matter discharged falls through this passage directly into the receptacle, and under ordinary conditions all soiling of the child's body or wrappings is avoided. It is to be noted that no appreciable amount of air can enter the box from below, and hence there are no currents upon the infant's skin. Furthermore, if the temperature makes it desirable, suitable coverings may be spread, blanket-like, over the top of the box or bed and be tucked in around the child.

Practical use of the apparatus shows that infants three or four weeks old acquire something like a habit of quickly taking advantage of the apparatus when placed in position thereon, thus eliminating perhaps five-sixths of the work normally required in caring for them in the matters under consideration.

Preferably the entire apparatus is of material which conducts heat slowly so that the infant may never be brought into contact with anything like cold metal. I have found that wood is satisfactory, but when used it is first made impervious to moisture in any suitable way, e. g., by enameling or by filling its pores with water-excluding material. The apparatus is thus readily kept clean or sterilized, or treated with antisepsics.

Obviously the bed or box may have a bottom.

What I claim is:

1. In apparatus of the class described, a box having top side plates sloping inwardly downward to an open channel between them and provided near one end with a transverse rod slightly above the plane of said plates.

2. The combination with a bottomless box or bed having at its top lateral plates sloping inwardly downward to a central open channel between them and adapted to receive below said channel a receptacle for

waste matter, of a bar extending transversely across the bed near one end and slightly above the plane of said plates.

3. The combination with a box or bed having at the top wooden side plates sloping inwardly downward to an open channel and adapted to support a pillow or mat at a little distance from one end of said channel,

of a wooden cross bar fixed above the plane of the plates and over that portion of the bed not intended to be covered by the mat or pillow.

In testimony whereof I hereunto affix my signature.

ROBERT L. DAVIS.
